UNITED STATES PATENT OFFICE.

JAMES M. G. FULLMAN, OF PITTSBURGH, PENNSYLVANIA.

FLOOR OUTLET-BOX.

1,251,497.

Specification of Letters Patent.

Patented Jan. 1, 1918.

Application filed November 17, 1908, Serial No. 483,051. Renewed June 13, 1916. Serial No. 103,583.

To all whom it may concern:

Be it known that I, JAMES M. G. FULLMAN, a citizen of the United States, residing at Pittsburgh, in the county of Allegheny and State of Pennsylvania, have invented a new and useful Improvement in Floor Outlet-Boxes, of which improvement the following is a specification.

My invention relates to improvements in 10 floor outlet boxes for electric conduits or wires.

The object of my invention is to produce a box the construction of which permits the ready insertion and removal of the receptacle 15 (which carries the terminals of the conductors) and the retention of the same in the box without the direct use of screws or similar fastening means; also relates to the production in the construction of said box of 20 means to produce a supporting shoulder or abutment for the lower end of the bell-shaped upper portion of the box. I accomplish these objects by means of the device hereinafter more fully described, reference 25 being had to the accompanying drawing forming part hereof, in which—

Figure 1 is a vertical central section of my improved outlet box.

Fig. 2 is the same the upper bell-shaped 30 portion being removed and the box closed by the removable plug.

Fig. 3 is a plan view of the same, the top, gasket and supporting ring being removed.

Fig. 4 is a perspective view of the strap 35 and electric receptacle with plug removed.

Fig. 5 is a modified form of the strap.

Fig. 6 shows a modified form of the means in the wall of the box to support the strap.

Referring to said drawings, 1 is the box, 40 the upper rim or edge of which is provided with an annular flange *a* in which screw-holes are formed for the purpose of enabling the top, 2, to be secured to said flange by screws, as shown in the drawings. Said box 45 is provided with orifices, *b*, *b*, in the sides and bottom thereof for the introduction of the conductors, 3 and are closed, when not in use, by means of the threaded plugs 4, 4, the said plugs having indentations *c* in 50 which a screw-driver or other suitable tool may be inserted for the purpose of screwing the said plugs in and out of said openings. The upper interior portion of said box, on opposite sides thereof, is provided with vertically disposed recesses 5, 5 each of which 55 terminates in a shoulder *d* at a point ap-

proximately midway its height. The said recesses are for the reception of the upwardly projecting members, *e*, *e*, of the strap or yoke 6, upon the horizontal portion 60 of which is suitably secured the receptacle or block 7 of porcelain or other suitable non-conducting material, which supports the terminals of the conductors in the box. The bent corners of the strap or yoke 6 rest upon 65 the shoulders *d* and the upper ends of the upwardly projecting members of said strap or yoke terminate under and approximately contact with the inner edge of the ring or plate 8, the outer edge of which is seated in 70 the annular recess *f* formed in the upper inner part of the box, the said plate or ring between the opening therein and the outer edge thereof being wider than said recess, whereby when the box is assembled, as shown 75 in the drawings, the strap and receptacle supported thereon are securely held in said box without the use of screws or similar fastening means and at the same time not only reducing to a minimum the space used 80 for securing means for the said receptacle but also producing a construction which enables the receptacle with its connected conductors to be quickly placed in and removed 85 from the box, without the inconvenience and consumption of time required in the present construction.

A gasket 9 is interposed between the top and the plug 10 and the ring 8. The central portion of the top is provided with an orifice 90 11 formed by punching or otherwise removing a portion of the top at such point, which constitutes the plug 10. The removed portion or plug 10, is crowded out around the edge thereof by forming in the under surface thereof an annular groove *h*, the orifice and the edge of the removable plug being screw threaded produces an economical method of forming this opening and a closing means therefor. The upper bell shaped 95 portion 12 of the box is provided with a screw thread which engages the corresponding thread in the edge of the orifice in the top of the box, whereby the said bell shaped portion can be screwed down upon the gasket, which is interposed between the said top and the ring 8, the said ring serving as a support to said gasket and enabling the bell shaped portion of the top to be tightly secured 100 against the same. The said bell shaped portion of the top terminates in a contracted 105 portion 13 in which a tube shaped insulation 110

- 14 is seated, through which the conductors are carried. It is manifest that vertically disposed ribs or projections 15 may be formed in the walls of the box in the relative position occupied by the recesses therein, and that the upwardly projecting members 16 of the strap may each be provided with a groove 17 to seat over said ribs to support the strap.
- 10 I claim as my invention and desire to secure by Letters Patent:—
1. A floor outlet box for electric wiring having a recess around the interior edge or rim thereof adapted to be closed by a cover 15 having an opening, and a projecting cap secured at said opening, in combination with a plate having an opening therein, the outer edge of said plate being seated in said recess, the said plate between the opening therein 20 and the outer edge thereof being of greater width than said recess.
  2. A floor outlet box having vertically disposed means formed in opposite sides of the box on the interior thereof for supporting the electric conductor terminal receptacle, in combination with a yoke supported by said means but unattached thereto, and a receptacle secured upon said yoke for the reception of the electric contacts or terminals.
  3. A floor outlet box having a vertically disposed slot in opposite sides of the box on the interior thereof, extending from the upper edge thereof a distance approximately one-half the height thereof, a yoke seated in 35 said slots and a receptacle secured upon said yoke for carrying the electric contacts or terminals.
  4. In combination, a floor box, an annular floor ring secured to the top thereof and 40 provided with a screw threaded inner periphery, a relatively rigidly supported annular gasket interposed between the floor ring and the rim of the floor box and projecting inwardly beyond the threaded inner periphery of the floor ring, a cap having screw threaded engagement with the threaded inner periphery of the floor ring and adapted to be screwed down into engagement with that portion of the gasket which projects inwardly beyond the inner edge of the floor ring and an electrical fixture mounted in 45 the box.
- In testimony whereof, I have hereunto signed my name in the presence of two subscribing witnesses.
- JAMES M. G. FULLMAN.
- In the presence of—
- CLARENCE A. WILLIAMS,
JOHN H. RONEY.
